FLOOR OUTLET RECEPTACLE

James W. Hudson, Elmhurst, Ill.

Application September 27, 1955, Serial No. 38,111

Term of patent 14 years

(Cl. D26—1)

Fig. 1 is a perspective view of a floor outlet receptacle which embodies my new design;

Fig. 2 is a plan view of the receptacle;

Fig. 3 is a front elevation of the receptacle; and

Fig. 4 is a side elevation of the receptacle.

The design resides in the features shown in full lines.

I claim:

The ornamental design for a floor outlet receptacle, substantially as shown and described.
